UNITED STATES PATENT OFFICE.

JOHN J. ROBERTS, OF LOUISVILLE, KENTUCKY, ASSIGNOR TO RECIPROCATING ELECTRIC TOOL COMPANY, OF LOUISVILLE, KENTUCKY.

ELECTRICAL HAMMER AND STONE-CUTTER.

1,284,930.

Specification of Letters Patent. Patented Nov. 12, 1918.

Application filed August 17, 1915. Serial No. 46,007.

To all whom it may concern:

Be it known that I, JOHN J. ROBERTS, a citizen of the United States, residing at Louisville, in the county of Jefferson and the State of Kentucky, have invented new and useful Improvements in Electrical Hammers and Stone-Cutters, of which the following is a specification.

My invention relates to electrical hammers and stone-cutters wherein new and useful designs in the construction of electro-magnets of the solenoid type have been devised, and new and useful means of operating and controlling said solenoid magnets through automatic and manually controlled electrical switches.

The objects of my invention are, — (1) to develop an electro-magnet of such a design as will generate and conserve for efficient circulation in a predetermined pathway of iron parts and intervening air-gaps in its field and armature the maximum number of magnetic lines for a given wattage of current and size of magnet; (2) to provide an electro-magnetic hammer of such shape and construction as will, at a certain desirable temperature, dissipate the internally generated heat units as rapidly as they are generated in normal operation, so that the hammer may so operate continuously at a desirable temperature; (3) to construct an electrical hammer of such design that the metallic impact of the hammer blows in normal operation shall take place outside of the magnetic field of said hammer; (4) to provide for an electric hammer a solenoid magnet with sliding, cylindrical armature of novel design adapted to direct the magnetic lines of said solenoid across the variable air-gap between the armature and the metallic field when energized; (5) to provide a new and useful electric switch of the cup-and-ball type having the fixed and the movable terminals adapted to make contact with each other promiscuously in a diversity of places in normal operation so that any one place on the contacting surfaces of the terminals touched at any one stroke of the switch, may have time to cool somewhat while contacts are being made in the succeeding strokes on various other places over the contact surfaces of said terminals; (6) to devise novel and simple means for operating said electrical hammer automatically through said cup-and-ball switch with the

alternate inward and outward impulses of said armature; (7) to provide novel means for cushioning the inward stroke of said armature to avoid metallic concussions in the magnetic field; (8) to provide novel mechanism for readily modifying the force of the hammer-stroke and also means for controlling the frequency of the hammer-stroke; (9) to provide a new and simple manually operated electrical switch adapted to start or stop the operation of the electric hammer at the option of the operator; (10) to provide novel means for readily changing the solenoid coil in the electrical hammer for another coil of the same size adapted to a different voltage; and (11) to provide novel attachments for said electrical hammer whereby the hammer form may be quickly changed to the form of an electrical stone-cutting tool. All of these objects are attained in the present invention, and the electrical hammer and stone-cutter illustrated in the accompanying drawings which form a part of this specification, is a practicable apparatus embodying the aforesaid novel means and other new and useful details of construction, arrangement and combination of parts, all of which, together with their functions will be described in detail with reference to said drawings, and will be definitely pointed out in the claims that follow the description.

In said drawings, Figure I is an elevation of my electrical hammer and casing assembled ready for operation. Fig. II. is a combination of a longitudinal section of the hammer and casing along the axis, with the manual and the automatic switch mechanism showing intact in elevation. Fig. III is a detail view, in elevation, of both the manual and the automatic switches and their contiguous and co-acting parts in their normally operative positions in respect to one another and to the electro-magnet, a fragmentary, longitudinal section of which, is shown in said Fig. III. Fig. IV is a view similar in every respect to Fig. III, and containing the same parts, but some of them are here shown in a different operative position from those of Fig. III.

Fig. V. which presents a view in every respect similar to that of Fig. IV., even to the relative positions of the moving parts, shows a modified form in which the conductors for the electric current of the solenoid are all

insulated from the ground of the hammer, as will be fully explained below.

Figs. VI. and VII. show horizontal projections of hammer-cap 8 and tool-cap 9 respectively detached from the spring-easing 7.

Fig. VIII. shows a side elevation of one of the tools 75 adapted to fit operatively into tool-cap 9.

Fig. IX. is a vertical projection of arm 64 10 with its contiguous parts 72 and 74 appearing in cross-section.

Fig. X. is a detail view of a fragmentary, longitudinal section of my electrical hammer in a plane of the axis, showing the tool-cap 9 attached and the stone-cutting tool 75 inserted therein and resting against the hammer-face 29 in position for operation.

Fig. XI. is a detail view of the terminal-end 22 of the solenoid spool, showing the 20 coil-terminals 19^a and 19^c anchored in the insulated terminal-plates 24 and 24^a respectively.

Fig. XII. is a side elevation of the terminal-end 22 of the solenoid spool and a 25 fragment of the coil 19, showing the insulated terminal-plates 24 and 24^a in elevation and the space 26^a between them.

Fig. XIII. is a vertical projection in detail of the inner part of the head-cap 5 30 adapted to fit operatively to the terminal-end of the solenoid spool as it appears in Fig. XI., the iron part 18 fitting inside the spool-cylinder 32 and the insulating blocks 26^a fitting into the deep spaces 26^a between 35 the terminal plates 24 and 24^a, as shown in Figs. XI. and XII., while contact-springs 25 and 27 rest against terminal-plates 24 and 24^a respectively, as shown in Fig. III.

Fig. XIV. is a side elevation in detail of 40 the head-cap 5, of my electro-magnet, showing in elevation one of the insulating blocks 26^a, the two contact-springs 25 and 27, with the two sharp contact-points 25^c at the raised extremity of spring 25. Spring 27 45 has similar points.

Fig. XV. is a detail in elevation of my 45 automatic switch of the cup and ball type showing the contact surface 52^x on the oval contact-end of the fixed terminal 52, and the cup-shaped contact-end 53^y of the movable terminal 53.

This invention has been developed for 50 general use where an efficient power-hammer or stone-cutter, large or small is desirable. It can be readily attached to a supporting 55 frame of any desirable kind and so left alone with its switches properly adjusted to work by itself indefinitely, as in pumping or other reciprocating-motor service. With this general purpose and the special objects aforesaid in view, I will now describe my invention in detail, pointing out and explaining the uses and the operations of the various parts and combinations thereof throughout 60 my invention, as illustrated in the drawings

hereinabove specified, in which similar letters and characters refer to similar parts throughout the several views.

In Figs. I. and II., 1 is the cylindrical casting of my electro-magnet. Its soft iron 70 forms a part of the external pathway of the magnetic lines of the solenoid within, as may be seen in Fig. II. The switch mechanism of my hammer is inclosed within the metal casing 2, whose outer end is closed by 75 means of the threaded cap 3, which can be screwed securely to the end of casing 2, as shown in Fig. II., where also may be seen that, into a central perforation and counterboring in cap 3, I have fitted loosely an insulating push-pin 4, movably secured therein by means of the cross-pin 4^a. Push-pin 4, when the hammer is not operating, is normally held in its outer position, as in Fig. II. by the spring-arm 46 clamped rigidly to 80 binding-post 45 by means of the thumb-nut 44 which also clamps the end of electric wire 42 to binding-post 45. Said binding post is insulated from plate 39, but rigidly clamped thereto by means of the nut 43^a and the insulating blocks 45^a.

Plate 47 fastened to the under side of arm 46 near its outer end is one terminal of the manually operated switch of the hammer, while the other terminal of said switch is 95 the tapered end 48 of the post 51 insulated from plate 39 but fixed therein by means of nut 49 and the insulating blocks 50. Into post 51 is rigidly fastened the contact part 52 which forms the fixed terminal of the automatic switch, the movable terminal being the part 53. When the hammer is at rest, therefore, the normal position of the manual switch 47—48 is open, while that of the automatic switch 52—53 is closed, as shown in 100 Fig. II. But when it is desirable to operate the hammer, push-pin 4 resting against spring-arm 46 is pushed inward forcing arm 46 to bend enough to press terminal-plate 47 against terminal-post 48, as shown in 105 Fig. IV., so that the current may pass through post 51 and the automatic switch 52—53 to the solenoid coil, as will be more fully explained hereafter. It should here be observed in Fig. III. that the reciprocating tappet-rod 72, sliding in and out of the channel 72^c through the parts 18, 5 and 30, is now on its inward stroke under the impulse of spring-pressed arm 64 hinged at 110 pintle 66 and engaging rod 72 at hinge-stud 67; and that tappet-disk 70, fastened rigidly to rod 72 with pin 71^a, has engaged tappet 58 of switch-segment 55 and is rocking that segment inwardly against the force of spring 56 coiled around pintle 57. This act 115 would soon rock segment 55 inwardly far enough to bring the switch-terminals 52 and 53 together, 53 being mounted on segment 55 by means of the flexible arm 54. Said act 120 would also rock segment 55 inwardly far 125 enough to bring the switch-terminals 52 and 53 together, 53 being mounted on segment 55 by means of the flexible arm 54. Said act 130

enough to allow detent 60, under the impulse of spring 62 coiled around pintle 63, to snap into notch 59 in segment 55, as shown in Fig. IV. Thus segment 55 may be 5 locked in its inward position with the switch-terminal 53 pressed against switch terminal 52 for a predetermined time, as will be hereafter shown. It should be noticed that the reciprocating tappet-rod 72, 10 under the impulse of the inwardly plunging armature 16, Fig. II., as will be herein-after explained, is shown in Fig. IV. on its outward stroke; and that tappet-disk 69 moving with rod 72 has already engaged 15 tappet 61, a rigid part of detent 60 hinged on pintle 63, and in this act would soon move tappet 61 far enough to disengage detent 60 from notch 59. And segment 55 thus released would suddenly rock back with its 20 switch-terminal 53 to the position shown in Fig. III.

It should also be observed that the parts 37 and 37^a, attached to arm 64 at crank-pin 38, move downward and upward with rod 25 72 and arm 64, as shown in Figs. III. and IV. respectively.

In Figs. II., III. and IV., I have shown 30 that the pathway of the electric current for energizing the solenoid coil 19 enters the ground of the hammer in the switch-terminal 53 and passes out through screw 73 and contact-spring 27 to terminal plate 24^a, and thence through the solenoid coil 19.

The head-cap 5 of the electro-magnet is 35 threaded around, as shown in Fig. XIV., and provided with a shoulder and adapted to be screwed securely into the head-end of casing 1 of the electro-magnet, until said shoulder impinges on the plane end of casing 40 1, as shown in Figs. I. and II. Head-cap 5 is also provided with a central perforation 72^c, concentric with which on the inner side is a comparatively large counterbore into which is closely fitted and screwed 45 the threaded end of armature-e-block 18; the other end of which block is provided with a large deep, central countersink adapted to receive the obtuncated conical end 17 of the reciprocating, cylindrical armature 16 50 which in operation slides back and forth, well-fitting, in the channel formed by the hollow metallic cylinder 23 of the solenoid spool on which is wound and fixed the insulated wire coil 19, as shown in Fig. II.

55 And the insulating washers 21 and 22, in Figs. II., XI. and XII., securely swaged on over the ends of cylinder 23, constitute the flanges of said spool. Now, the perforation 72^c of head-cap 5 is extended on through 60 block 18, as illustrated in Figs. II. and III.

The tail-cap 6 of my electro-magnet is provided with a shoulder and a reduced portion with threaded perimeter similar to head-cap 5, as illustrated in Figs. II. and 65 XIV., tail-cap 6 being adapted to be screwed

securely into the tail-end of casing 1, bringing the plane face of said shoulder firmly against the plane-finished end of said casing. Also through tail-cap 6 is a large central boring 6^a whose wall inside is chased 70 around with a fine, V-shaped, helical groove, presenting a shallow-threaded surface, and also similarly threaded is that portion of armature-shank 14 which is directly opposite the threaded wall of boring 6^a while 75 armature 16 is in its normal position of rest. These adjacent surfaces are threaded to facilitate the passage of the magnetic lines of force through the surfaces of the adjacent parts, at the moment when said armature is 80 starting on its inward stroke.

Concentric with said boring 6^a at its inner end is a shallow counterbore 6^b, into which is swaged a metal washer 20 flush with the inner face of cap 6. Now, the shoulder 15, 85 a 45-degree bevel, is the reduction in diameter of armature 16 to the smaller diameter of armature-shank 14. And the central perforation in washer 20 has a diameter less than the diameter of the central boring 6^a, 90 so that the inner rim of washer 20 extends inward slightly beyond the threaded wall of boring 6^a; and the inner edge of this rim of washer 20 is beveled and adapted to fit evenly against the beveled shoulder 15 when 95 armature 16 is resting in its outermost position, as illustrated in Figs. II. and X. Washer 20, therefore, serves as an abutment for shoulder 15 of armature 16 in its outward plunge, should the hammer-head fail 100 to meet with other resistance sufficient to arrest it in the hammer-stroke. It should also be explained here that the central perforation in washer 20 has a greater diameter than armature-shank 14 which passes 105 through said perforation without touching washer 20, the bearings of said armature-hammer being channel 23 and the central boring in stay-block 12.

In my electro-magnet, as illustrated in 110 the drawings herewith, the armature 16 with its essential parts 14, 15 and 17, and the casing 1 with its caps 5 and 6 and their parts and joints, have all been studiously designed, both in their relative delineations 115 and in their comparative sizes, through extensive experimentation, and so adapted to carry in this predetermined pathway of efficient circulation a very high percentage of the magnetic lines generated within the solenoid coil, to the end that the most powerful hammer-stroke possible may be delivered for a given wattage and size of magnet. The iron casing-caps 5 and 6 are both comparatively heavy and round-shouldered to counteract leakage and straying of magnetic lines as they make their end-turns from armature or casings. The obtuncated conical nose 17 of the cylindrical sliding armature 16 is adapted to fit into the deep, central coun- 120 125 130

tersink of armature-block 18 on the inward stroke of armature 16. Thus the parts 17 and 18 are adapted to allow a long reciprocating movement of armature 16 with a 5 comparatively narrow air-gap 17^x. Thus I have, in a great measure, counteracted the magnetic reluctance of the variable air-gap 17^x of operation. Also I should explain that the peculiar shapes of the parts 17 and 18 10 and the constricted neck 14 of the armature 16, have all been adapted to congest the magnetic lines toward the axial zone of armature 16 to help minimize the tendency of said lines to leap across between casing 1 15 and armature 16 instead of crossing the air-gap 17^x of operation as lines of efficient force.

Metal stay-block 12 has been adapted to fit closely on the outside of tail-cap 6 to 20 which it is securely fastened by means of the screws 13, 13, Fig. II. Stay-block 12 is provided with a large central boring adapted to allow the non-threaded outer end of armature-shank 14 and also the inner end of 25 hammer-neck 10 to slide through easily, though close fitting. And block 12 is also threaded around its perimeter. Now, spring-casing 7 which incloses hammer-spring 11, is provided with a thread around the inside 30 of the inner end and with a beveled edge, and has been so adapted to be screwed on securely over block 12, fitting closely against cap 6, as shown in Fig. II. The outer end of casing 7 is also threaded around the inside 35 circumference and adapted to receive and hold hammer-cap 8 or tool-cap 9 whose inner ends are threaded around, as shown in Figs. VI. and VII., and otherwise adapted to be securely screwed into the outer end of 40 spring-casing 7, as illustrated in Figs. II. and X.

To further counteract leakage and straying of the magnetic lines from efficient circulation through my solenoid magnet, the 45 armature-shank 14 at its outer end has been terminated in a convex surface, and centrally bored to a suitable depth, which boring is threaded. Then the inner end of hammer-neck 10 is concaved and fashioned with 50 central threaded post 10^x and adapted to screw securely into shank 14 so as to fit evenly against said convex surface of the end of shank 14, as shown in Figs. II. and X. Said hammer-neck 10 is made of a suitable 55 non-magnetic metal alloy, preferably containing phosphorus and a high percentage of copper, which I have found to be diamagnetic to a marked degree under the effect of the rapid operative alternations in 60 the electro-magnetic field. These facts, therefore, both of contour and of composition in these parts deflect the axially inclined magnetic lines of force, bending them to the desirable declination along the plane of casing-cap 6 where they readily pass the slight 65

air-gap between said casing-cap and armature and so are conserved for efficient circulation, as I have previously set out among the objects of my invention.

In the outer end of hammer-neck 10 is a 70 large central boring with threaded wall. The steel hammer-head 29 with slightly convex face has a larger diameter than neck 10, and is provided on its plane inner side with a heavy central lug 29^x threaded and adapted to be screwed tightly into said central boring until the plane outer end of neck 10 impinges on the plane inner side of head 29 in an even joint which is then made fast by means of a pin 29^a swaged into a transverse 75 80 boring through neck 10 and lug 29^x, as shown in Figs. II. and X. Hammer-head 29, as I have said above, has a greater diameter than hammer-neck 10, and is also adapted to act as an abutment for the main spring 85 11 of the hammer, which has been fitted on over hammer-neck 10, so that the inner end of said spring abuts against stay-block 12 while the outer end of said spring pushes 90 against the rim of the inner side of hammer-head 29, between which two stays said spring is held under desirable tension for the normal operation of the hammer.

In Figs. III. and IV., the stay-block 30 is a large disk of non-magnetic metal which 95 constitutes the foundation of the switch mechanism and its housing. The outer or upper face of block 30 is plane, while the inner or lower face is concaved and adapted to fit centrally and evenly on over the outer 100 side of head-cap 5 to which block 30 is rigidly fastened by means of the screws 31, 31, as shown in Figs. III. and IV. Around its perimeter block 30 is threaded; and switch-casing 2, a hollow cylinder of non-magnetic 105 metal is also threaded around on the inside from its inner or lower end back a little way, and its end section is provided with a bevel made to fit the curvature of the shoulder of head-cap 5, said end of casing 2 being so 110 adapted to be screwed on over stay-block 30 until the beveled end of casing 2 is forced tightly against the rounded shoulder of head-cap 5, as illustrated in Figs. I., III. and 115

Into the upper side of stay-block 30, at equal intervals around the disk near its edge, are fastened by means of threaded lugs, three square posts, 35, 35^a and 35^c, of non-magnetic metal, as shown in Fig. III. Post 120 35 in the foreground near dash-pot 36 is in fragments contiguous to block 30 and disk 39 above; post 35^c is shown plainly in the background of Fig. III.; and post 35^a is shown in said figures well to the left near 125 switch-post 51. These three square posts, 35, 35^a and 35^c form the rigid support for plane disk 39, upon which is mounted the binding post 43^a insulated from disk 39 by means of the insulating blocks 43^b. Bind- 130

- ing-post 45 and switch-post 51, as I have previously explained, are also mounted in disk 39. There is a central perforation also in disk 39, into which on the inner side is swaged and soldered the short metal tube 65, said part being adapted to allow the outer end of the reciprocating tappet-rod 72 to pass entirely through it, as shown in Figs. IV. and V., and sleeve 65 acts as one of the 10 bearings of tappet-rod 72, the other bearing of which is the central perforation 72^c in head-cap 5 continued through blocks 18 and 30, Fig. III.
- Pintle 57 is fixed into one side of post 35^a, 15 and against the opposite side of said post is clamped by means of screws 74^a the metal plate 74 into which the pintle 66 of arm 64 and the pintle 63 of detent 60 are fixed, see Figs. III and IV.
- 20 Spring 56 coiled around pintle 57 to actuate segment 55 outwardly has its lower end braced against block 30 and its upper end looped over segment 55 and bearing against the extended portion which carries arm 54, 25 Figs. III. and IV. Spring 62 coiled around pintle 63 has one of its ends looped over detent 60 while the other end is braced against post 35^a, Figs. III. and IV.
- The air dash-pot 36 is mounted on block 30 by means of two ears 34 fastened to block 30 with screws on diagonally opposite sides of said dash-pot and two lugs 33 fixed in the opposite sides of dash-pot 36, and adapted to act as pintles in the perforations in said ears, as illustrated in Figs. III. and IV., so that dash-pot 36 may be easily rocked back and forth on a radial line of stay-block 30, to adapt its position to the movements of dasher-rod 37 attached to the end of swinging-arm 64 by means of the crank-pin 38. The inward movement of dasher 37^a, shown with dotted lines in dash-pot 36, is retarded or accelerated by means of the screw pins 45 valves 32, by which the air ports near the bottom of said dash-pot may be gradually opened or closed. The adjusting of these valves, therefore, determines the number of hammer-strokes per minute delivered in 50 operation; for swinging arm 64, hinged at pintle 66 and impelled downward by spring 66^a, can move downward only as fast as dash-pot 36 will allow it, being attached to dasher-rod 37 at crank-pin 38; now, arm 64 is also engaged to tappet-rod 72 loosely but securely by means of the hinge-stud 67 fixed in arm 64 and passing through a hole larger than itself in tappet-rod 72, so that 55 said arm and rod move up and down together. But tappet-rod 72 must complete its cycle of movement for every stroke of the hammer after the first one; consequently, if arm 64, under control of dash-pot 36, can make but nine cycles a minute 60 then the hammer will make but nine strokes in the same time. But when the valves 32 are set open wide enough for arm 64 to complete nine-hundred cycles, more or less per minute, then the hammer will deliver nine hundred strokes more or less, per minute, as 70 set forth in the stated objects of my invention.
- The hole in tappet-rod 72 where hinge-stud 67 passes through is made larger than said stud to compensate the arc described by 75 stud 67 in its operative movement on pintle 66, while tappet-rod 72, in its normal operation, must move in a straight line.
- Arm 64 is double, one part passing on the hither side of rod 72 and the other part 80 passing on the yonder side, as illustrated in Fig. IX. The two parts are held securely together by means of pintle 66, crank-pin 38, hinge-stud 67 and stay-pin 64^a, against which one end of spring 66^a coiled around 85 pintle 66, pushes, while the other end of said spring is braced against post 35^a, as shown in Figs. III. and IV. Spring 66^a is strong enough to force tappet-rod 72 inward to its limit of operation, against the resistance of 90 dash-pot, friction and spring 56 which must be overcome in the inward movement of tappet-rod 72 as disk 70 moves down against tappet 58.
- Tappet-rod 72 in the inner end has a deep 95 central boring with internal threads into which is screwed a long threaded rod 72^a close-fitting in the threads and adapted to be set with more or less of its end standing out of said boring in rod 72, as illustrated in 100 Fig. II. This threaded internal rod 72^a is adapted to act as an auxiliary of rod 72 for controlling the length, and consequently the force, of the hammer strokes within their normal limits, as I will duly explain in detail. This feature I have previously mentioned as one of the objects of my invention.
- The three square posts 35, 35^c and 35^a, as I have previously said, are provided at their 110 inner ends with threaded axial lugs which screw into block 30, but at their outer ends they have axial borings threaded. Now the three round posts, each designated 41, mounted on disk 39 directly over the square 115 posts 35, 35^c and 35^a, are provided at their inner ends with threaded axial lugs which pass loosely through perforations in said disk properly located with respect to the threaded borings in said square posts below, 120 into which said lugs are firmly screwed, so that the three posts 41 make a strong and rigid support for disk 40 which is fastened to the tops of said posts with the screws 41^a. Disk 40 is adapted to brace casing 2 internally where the wire-vent 2^x is cut through, 125 and to give rigidity to the upper part of the hammer. There is a central perforation 40^a in disk 40 adapted to allow push-pin 4 with its transverse stay-pin 4^a to pass readily 130

through when cap 3 is being removed or replaced on casing 2.

In the inside of cap 3, in the central portion through which passes push-pin 4, is the set-screw 3^a adapted to be screwed in against push-pin 4 to hold said pin fast in any desirable position, that is, with the switch 47-48 open or closed, as shown in Fig. III.

In Fig. VIII, the stone-cutting tool 75 is shown in full side elevation apart from the hammer. The cutting end 75^a is sharpened with converging bevels. The round shank 75^c is adapted to fit loosely into the channel 9^x of tool-cap 9, Figs. VII. and X., as far as the square shoulder-rim 75^x which is adapted to stop said tool against the outer end of tool-cap 9, Fig. VII.

In Fig. X. tool 75 is shown entering channel 9^x of cap 9 as far as hammer-head 29, which has in the counterbore of channel 9^x ample room to work efficiently.

In Fig. II. may be seen a full longitudinal section, in elevation, of my solenoid spool and coil assembled and fitted into its place in the casing of the magnet ready for operation. There are shown its hollow spool-cylinder 23, its insulating spool-heads 21 and 22, its coil of insulated wire 19, of which one terminal 19^c leads from coil 19, also Fig. III., through spool-head 22 into metal terminal-plate 24^a to which the end of 19^c is soldered; while the other terminal 19^a of said coil is shown in the right side of Figs. II. and III., leading from coil 19 through the outer edge of spool-head 22 into metal terminal-plate 24 to the outer edge of which the terminal 19^a is soldered. The terminal plates 24 and 24^a may be seen in Fig. XII., a side elevation, and Fig. XI. a vertical projection of terminal spool-head 22, showing terminal-plates 24 and 24^a fastened to insulating spool head 22 by means of the four clamps 24^x. In Fig. XI. is also shown the end sections of terminals 19^a and 19^c as soldered in the plates 24 and 24^a respectively.

In Figs. II. and III. is also shown a sectional view of the annular ridge 5^a on the inner side of head-cap 5, which is adapted to facilitate the lateral passage of magnetic lines between armature-block 18 and head-cap 5. On the inner side of cap 5 between said annular ridge and the edge of the threaded portion of said head-cap is fitted the insulating washer 26 clamped to cap 5 by means of screws 28 and 73 in Fig. II. and by screws 26^a in Fig. XIII., where washer 26 is shown in a vertical projection. On washer 26 are mounted the insulated contact-spring 25, with screws 25^a, and the non-insulated contact-spring 27, held by screws 73 passing through washer 26 into head-cap 5, as shown in Figs. II. and XIII. Screws 73 are adapted to conduct the electric current between contact-spring 27 and the ground of

the hammer, so that said electric current may run through cap 5 and other metal parts of said hammer to the arm 54 and switch-terminal 53 of the switch 52-53, where it passes through at predetermined intervals 70 under automatic control in the normal operation of the hammer, as will be explained hereafter.

In assembling my electro-magnet we screw head-cap 5 into the head-end of casing 1; 75 then coil 19 on its spool should be pushed head-first into casing 1 in such a way that spaces 26^x between the terminal-plates 24 and 24^a, Fig. XII. shall coincide with insulating blocks 26^a, Fig. XIII., and contact-springs 25 and 27 shall fall on contact plates 24 and 24^a respectively where good electrical contact with said plates is made with the sharp points 25^c of spring 25 and 27^c of spring 27. When the solenoid coil is thus seated with block 18 inside of spool-cylinder 23, as illustrated in Fig. II., tail-cap 6 with its contiguous parts, armature hammer-neck, spring, etc., all assembled, should be screwed into the tail-end of casing 1 tightly. 90 This operation will close the joint between cap 6 and casing 1, and also set the sharp points 25^c and 27^c of the contact-springs 25 and 27 hard against contact-plates 24 and 24^a respectively, so that the electric current 95 passes between said contact parts readily regardless of vibrations in the hammer. The other mechanism and cases are easily assembled.

One of the insulated conductors 42 of the 100 operative wire of the hammer terminates in binding-post 45, and is easily attached or detached at this point; the other conductor 43 has a terminus in binding-post 43^a, where connection is made with its inner insulated 105 splice which runs down through perforations in disk 39, block 30, cap 5, washer 26 and contact-spring 25, in which it is permanently soldered, see Figs. III. and XII.

I will now describe the operation of my 110 electrical hammer. Fig. I, as I said, represents a side elevation of the hammer assembled ready for operation. Through the port 2^x in casing 2 near cap 3, issue the electric conductors 42-43 from the hammer-terminals within, see Fig. II., out to connect with wires running to the source of the electric current. In practice, a short, flexible, double conductor terminating in a suitable coupling-plug, is so attached to each hammer 115 for convenience in connecting to the current.

Now when the connections to the current are made and the hammer is held in position on the work, we press inward on pushpin 4 which forces arm 46 down closing manual 125 switch 47-48. If now, for convenience of explanation, we suppose that the current is running in on conductor 42, and out on conductor 43, we may say that, at the closing of switch 47-48, the current runs down ter- 130

51 terminal 48 through insulated switch-post 51 and on through the automatic switch terminals 52 and 53 and down along parts 54 and 55 to the general ground of the hammer, whence it runs through screw 73, contact-spring 27 and terminal-plate 24^a, from which it passes through the terminal 19^c and then circulates all through insulated coil 19, Figs. II. and III.; and leaving coil 19 through terminal 19^a, Fig. III., it passes through terminal-plate 24 and insulated contact-spring 25 to conductor 43 and thence out to its line again, having completed efficiently its predetermined circuit of the hammer.

15 But in Fig. V. a different course in the energizing current of the solenoid is shown. And Fig. V., as I have previously said, is designed to illustrate how all the conductors of the electric current for the solenoid are 20 insulated from the ground of the hammer, a feature that would be desirable under some conditions of work. In Fig. V., therefore, the side of the line indicated as conductor 43 takes the same course as it takes in the 25 other Figs. II., III. and IV.; and the side of current represented in line 42, follows the same course as in the other Figs. II., III. and IV., from binding post 45 through arm 46, switch 47—48, switch-post 51, switch 30 52—53 to flexible arm 54; but from arm 54, instead of running to the ground of the hammer as shown in the other figures, from arm 54 the current, as illustrated in Fig. V., takes a new course into loop 42^a formed on the 35 end of flexible arm 42^a which passes through a perforation in disk 39 to binding-post 42^c fixed in the insulating block 41^c fastened to post 41 with screws 41^a. From binding post 42^c the current flows through insulated wire 40 42^a leading down through a straight channel drilled through block 30, cap 5 and insulating washer 26, where it is soldered into contact-spring 27, which in this construction is insulated from the ground of the hammer, 45 having no screws 73 passing through it to connect it electrically with the ground of the hammer. In Fig. V. washer 26 is held in place by screws 28 and 73^a all insulated from the contact-springs 25 and 27. In Fig. V. 50 is also shown the insulating-block 55^a fastened to the upper portion of segment 55 with the rivets 55^c. In a longitudinal slot at the upper end of insulating block 55^a the lower end of the flexible arm 54 is fastened 55 with the rivets 55^a. Therefore, in the hammer construction shown in Fig. V., as I have said above, the operative electric current of the solenoid never reaches the ground of the hammer.

60 Now, the circulation of the electric current through the solenoid coil develops powerful magnetism in the iron parts of said electro-magnet, and under the influence of said magnetism, armature 17 and all its attached parts leap inward toward armature-block 18, and, under certain conditions, would clash against said block with great force. But this clash is prevented by two things, the spring 11 and the controlling function of tappet-rod 72, as I will shortly 70 explain. When armature 16 under magnetic impulse passes inward, taking the hammer part with it, spring 11, with its inner end abutting block 12 and its outer end braced against the rim of the inner side of hammer-head 29, is gradually set back under increasing tension, as head 29 approaches block 12, until just before nose 17 comes in contact with block 18, the spirals of helical spring 11 are crowded together into contact with 75 one another forming a practically solid resistant cylinder between block 12 and the approaching head 29, so that further movement of armature 16 inward is completely estopped, spring 11 having been adapted in 80 size of wire and number of spirals so to stop the inward movement of armature 16 at a predetermined place in its operation. While the outward plunge of armature 16 in normal operation, is of course stopped by 85 the direct impact of the hammer-head 29 upon the work. Consequently, although my electrical hammer strikes nearly a thousand powerful blows a minute, no concussion 90 takes place within the limits of the magnetic 95 field, an important feature listed as one of the objects of my invention.

In connection with this subject, it might not be out of place here to explain that 100 spring 11 is so graduated in strength that nearly all the energy of the inward impulse of armature 16 is consumed in setting back spring 11 to its maximum tension for work, so that there is left very little surplus energy of the inward-moving armature 16 105 to be counteracted by the resistant spirals of spring 11 crowded together, as above explained.

The other way of limiting the inward movement of armature 16 by means of the 110 controlling function of tappet-rod 72, mentioned above, is effected by allowing the inner end of rod 72 to stand through block 18 down into air-gap 17^x far enough for inward-plunging nose 17 to strike it and 115 push it outward to cut the electric current from the solenoid, a fact which instantly destroys the magnetism then acting on armature 16 and allows it to plunge outward again under the impulse of spring 11, as I 120 will now explain in detail.

When the solenoid is energized by the circulating current, armature 16, as I have said above, plunges inward across air-gap 17^x forcing the air out through channel 72^a 125 through which slides loosely tappet-rod 72; and near the upper end of air-gap 17^x the small end of nose 17 strikes the end of tappet-rod 72 pushing said rod upward together with its co-acting parts, as illustrated 130

in Fig. IV. Now, tappet-block 71, with its tappet-disks 60 and 70 all rigidly fastened to rod 72, leaps upward with said rod, moving tappet 61 far enough to disengage 5 detent 60 from notch 59, and segment 55 under pressure of spring 56 rocks backward and so opens switch 52-53, thus cutting automatically the current to the solenoid coil and allowing said armature to fly outward again under the recoil of spring 11 as I have previously described. This sudden withdrawal of nose 17 from its pressure on the end of rod 72, allows said rod to move again inwardly under the pressure of spring 15 66^a and the control of dash-pot 36, as previously described, until tappet disk 70 reaches tappet 58, a rigid part of switch- 20 segment 55 and thus rocks said segment inward again, Fig. III, until switch 52-53 is closed and notch 59 has been carried far enough for detent 60 to snap into it and so lock switch terminals 52 and 53 together again where they will remain in contact 25 passing the current through the solenoid coil again till armature 16 magnetized again plunges inward and pushes tappet-rod 72 upward again to cut the current at the switch 52-53 as before. In this way my electrical hammer normally operates 30 automatically with very strong and very rapid strokes, so long as the current is admitted to the hammer terminals 45 and 43^a and the manual switch is held closed.

It can now be readily seen that tappet- 35 rod 72 in normal operation is driven upward suddenly with great force at every inward plunge of armature 16, and that the inertia and other resistance of the dasher 37^a and contiguous parts would throw 40 much stress and work upon hinge-stud 67 through the enlarged hole in rod 72. For this reason I have made the sleeve 68, a long rigid part of block 71, long enough to reach up to the rounded part 64^c of the 45 arm 46, where sleeve 68, is adapted to take all the stress of suddenly lifting arm 64 and its attachments at the upward plunge of armature 16 and rod 72. The lower side of the part 64^c has been rounded to rock 50 easily on the upper edge of sleeve 68.

An explanation of the functions of threaded rod 72^a can now be readily understood from the previous detailed description of the functions of tappet-rod 72. Rod 55 72, when made, should be adapted to stand down in the air-gap 17^x about far enough to allow the armature 16 to make a complete stroke by the time rod 72 and its disk 69 is pushed up high enough to cut the current from the solenoid. Then when rod 72^a is screwed into rod 72 nearly flush with its lower end, plunging armature 16 will in operation make a complete movement inward and spring 11 will be set to its maximum tension and so in recoil will deliver a

maximum hammer blow, but if rod 72^a should be set standing far out of the end of rod 72 and reaching nearly across the air-gap 17^x the small end of the nose 17 of armature 16, would, shortly after starting inward, meet the end of rod 72^a and quickly push disk 69 against tappet 61 and so cut the current by means of its co-acting parts; and armature 16 carrying hammer 16-29 would fly back with only a moderate blow, 75 having completed perhaps less than one-half of its full stroke. By adjusting the lower end of the threaded rod 72^a, therefore, so that it will stand out of rod 72 at a greater or less distance from the end of nose 17, we 80 shall get a correspondingly greater or less blow from the hammer in operation, as I have previously set out in the statement of the objects of my invention.

Another stated object of my present invention is to provide means for dissipating the heat units generated in the solenoid magnet, so that the hammer may operate continuously at a desirable temperature. This is effected by making the solenoid coil long 90 and comparatively thin to allow a suitable external surface for radiation, and by forcing a change of air in the internal air-gap 17^x through the perforation 72^c at every stroke of the hammer, and by giving the 95 magnet a heavy iron armature 16 and armature block 18 with heavy iron end-caps 5 and 6, adapted to afford ready convection of internal heat.

It can now also, be readily seen that solenoid coil 19 and its essential parts, 21, 22, 23, 24 and 24^a, being all securely and permanently fastened together in one strong package, can be readily removed from the 100 casing of the magnet, so that another coil 105 for a different voltage may be quickly adjusted in its place.

In closing this specification I would direct attention to the new and useful construction and the peculiar operation of my 110 automatic switch 52-53-54, which opens and closes nearly a thousand times a minute while the hammer is operating.

Now in the case of a direct-current and electro-magnet, it is well known that when 115 the electric circuit is broken, an electric spark springs out from the one terminal of the severed conductor, tending to form an electric arc across to the other terminal of the break. This so-called induction spark at the opening of an electric switch cannot well be entirely eliminated or avoided by any switch mechanism at present generally known, and the spark is detrimental to the switch, in that it heats and 120 burns away the terminals. Consequently, by much experimenting, I have devised and invented an electric switch mechanism 52-53-54, Fig. XV., which in normal operation works with practically cool termi- 125 130

nals and slow erosion. This result I have accomplished in part by making the contact-end of the fixed terminal 52, Figs. III, and XV., of such a shape that the contact part 5 52^x would present a comparatively large surface for contact instead of a single point, so that successive contacts might be made on it in a multiplicity of places promiscuously over the broad surface of the contact 10 part 52^x; and by making the contact-end of the movable terminal 53 deeply concaved or cup-shaped so that the contacting part 53^y of this terminal should also be a comparatively broad area instead of a single point 15 for contact with terminal 52.

Now by devising a unique attachment feature in connecting terminal 53 to the flexible and oscillating arm 54 Fig. XV., so that terminal 53 rocks freely to every point of its 20 equatorial circumference, I have completed my device for distributing the successive electrical contacts indiscriminately around over the broad surfaces 52^x and 53^y, so, that in the normal operation of the switch, the 25 induction sparks may spring out successively from a multiplicity of points, one after another, over the comparatively broad area of the contact surfaces 52^x and 53^y, instead of shooting out successively from any 30 one point of the terminal, which would cause excessive heat and erosion of the point.

Terminal 52 is of course made of platinum, and is set rigidly and securely into metal block 51. At the contact-end, terminal 35 52 is conical and rounded at the extremity; but terminal 53 at its contact-end is provided with a cup-like hollow adapted to fit very loosely on over the conical end of terminal 52. At the outer end of terminal 53, which is also made of platinum, is an axial lug 53^x, which after being passed 40 through a lateral perforation larger than said lug in the end of flexible arm 54, is properly headed in such a way as to attach terminal 53 to arm 54 securely but loosely. Terminal 53 is thus adapted to rock slightly 45 in all directions in its joint with arm 54. Now in the normal operation of the hammer, flexible arm 54 oscillates with great rapidity 50 slightly rocking terminal 53 indiscriminately in every direction, so that at one stroke the terminals 52 and 53 may make or break their contacts on one side and at the next stroke, on another side, and so on indefinitely seldom striking in the same places twice in succession. And in practice these 55 peculiar switch terminals 52 and 53 have been found to be fairly cool and durable in operation, as set out in the stated objects of 60 my invention.

Having thus described the features of my invention, the operation, construction, arrangement and combination of its parts, what I claim in my invention as new and 65 useful and desire to have outlined in Letters

Patent, is set forth specifically in the following claims:—

1. In an electrical hammer of the kind described, a reciprocating electric motor of the solenoid type for operating said hammer, a magnetic plunger sliding in said solenoid motor, an electric circuit to said motor, an automatic switch for opening and closing said circuit intermittently, combined with a sliding rod extending longitudinally into 70 the interior of said solenoid and adapted to be pushed outwardly by said plunger, spring-pressed devices for pushing said rod into the solenoid again, and co-acting mechanism between said rod and the said switch 75 adapted to open and close said switch as the sliding rod is pushed alternately in and out of said solenoid.

2. In an electrical hammer of the kind described having a solenoid wound on a hollow 80 spool, a reciprocating armature adapted to slide operatively in said spool and carrying a hammer-portion on its outer end; an electric circuit in said hammer to connect the solenoid for actuating said armature to 85 make its inward stroke, and a driving spring on said hammer-portion adapted to force said armature to make its outward stroke; combined with a switch in said circuit; a spring pressed lever; a reciprocating rod 90 attached thereto and extending into said spool and adapted to close said switch when pushed by said lever a predetermined distance into said spool and to open said switch when pushed outward again a predetermined 95 distance by the armature; an axial screw in the inner end of said reciprocating rod adapted to be set partially out of the rod a greater or less distance to give greater or 100 less length operatively to said rod that the rod may be met earlier or later respectively by the inwardly-moving armature and so pushed outward its predetermined distance to open said switch earlier or later in the stroke to make a correspondingly lighter 105 or heavier hammer-stroke in normal operation.

3. In an electrical hammer having a solenoid wound on a hollow spool, a reciprocating armature adapted to slide operatively 110 in said spool and carrying a hammer-portion on its outer end; an electric circuit in said hammer to connect the solenoid for actuating said armature to make its inward stroke, and a driving spring on said hammer-portion adapted to force said armature to make its outward stroke; combined with a switch in said circuit; a spring pressed lever; a reciprocating rod attached thereto 115 and extending into said spool and adapted to close said switch when pushed by said lever a predetermined distance into said spool and to open said switch when pushed outward again a predetermined distance by the armature; an axial screw in the 120
